J. TORCHIA.
LADY'S HOUSE DRESS.
APPLICATION FILED MAR. 19, 1920.

1,365,749.

Patented Jan. 18, 1921.

UNITED STATES PATENT OFFICE.

JOSEPH TORCHIA, OF CINCINNATI, OHIO.

LADY'S HOUSE-DRESS.

1,365,749.

Specification of Letters Patent. Patented Jan. 18, 1921.

Application filed March 19, 1920. Serial No. 387,048.

To all whom it may concern:

Be it known that I, JOSEPH TORCHIA, a citizen of the United States, residing in Cincinnati, in the county of Hamilton and State of Ohio, have invented certain new and useful Improvements in Ladies' House-Dresses, of which the following is a specification.

The object of my invention is to provide means for automatically adjusting and regulating the size of the dress around the waist to adapt it to persons of varying sizes or to varying conditions of the wearer.

My invention consists in providing the dress with a waistband having a longitudinal passage-way therein, with an opening at each end thereof, a button adjacent each opening and an elastic band inserted in said passageway through said openings and detachably connected to said buttons to automatically adjust the goods to the form and size of the wearer.

My invention also consists in the details of construction and arrangement and in the parts and combination of parts as herein set forth and claimed.

In the drawings:

Figure 1 is a perspective view of the dress in use looking at it from the front;

Fig. 2 is a perspective view looking at it from the rear;

Fig. 3 is a side elevation of the detachable elastic band;

Fig. 4 is a rear view of a portion of the dress on an enlarged scale illustrating my invention;

Fig. 5 is a section on the line 5—5 of Fig. 4; and

Fig. 6 is a section on the line 6—6 of Fig. 4.

In the embodiment of my invention as illustrated, and which shows a preferred construction, the waistband 7 comprises two plies 8 and 9 secured to the waist 10 along its upper edge by stitches 11 and to the skirt 12 along its lower edge by stitches 13, forming a passageway 14 between said plies and said stitches respectively throughout a portion of its length, preferably the rear, near one side of which an opening 15 extends through ply 8 to passageway 14 and at the other side an opening 16 is formed in ply 8 to communicate with said passageway. A button 17 is attached to said band near opening 15 and button 18 is attached to said band near opening 16.

An elastic band 19 having a metal eyelet 20 upon one end and a similar metal eyelet 21 on the other end is adapted to be inserted through said openings and passage-way and to be attached to said buttons by means of said eyelets. When so attached, the band, with the exception of the eyelet, is concealed within the waistband and the tension of the elastic band automatically 60 draws the fullness of the goods and supports the gathers thus formed in compact and snugly fitting form to the body of the wearer, as shown in Fig. 2, and at the same time, draws any excess fullness of the goods 70 from the front to give it a neat fit as shown in Fig. 1.

The metal eyelets 20 and 21 respectively are formed of wire bent in the shape shown in Fig. 3, the larger end having the wire 75 formed straight to receive and engage the looped end of band 19 and tapering therefrom toward the free end which is formed circular but with a contracted neck between the tapering portion and the circular portion in order that the threads or other button fastening means may be engaged therewith by first inserting the button through the tapering portion and then drawing it above the circular portion, thus forming a 80 very convenient and efficient detachable connecting means between the band and the garment.

The tapering metallic eyelets provide convenient and efficient means for inserting the 90 elastic band through the openings and passage-way.

An important feature of my invention consists in providing the detachable elastic band for the reason that an elastic band 95 permanently secured to the dress will lose its elasticity upon being laundered, whereas, with the use of my invention, the elastic band may be readily detached and removed before the dress is laundered, and then easily 100 and quickly inserted for use after it is laundered, thus preserving the integrity of the elastic band.

It will be apparent that my invention is capable of some modification without departure from the scope or spirit thereof, as for instance, the passage-way may be formed between the waistband and the body of the goods, instead of being formed between plies of the band interposed between the waist 110 and skirt.

Having described my invention and its

manner of use, what I claim as new and desire to secure by Letters Patent is:

In a house dress having a waist and skirt, a two ply waistband overlapping the lower edge of said waist and the upper edge of said skirt and stitched to each of said edges respectively whereby a longitudinal passage-way is formed in said waistband between said waist and skirt, said waistband

having openings leading to said passage-way, a button adjacent each opening, an elastic band, and a longitudinal tapering eyelet on each end of said elastic band, said band being adapted to be inserted in said openings and passage-way and said eyelets being adapted to detachably engage said buttons respectively.

JOSEPH TORCHIA.
